SCAVENGE PUMPING MEANS FOR INTERNAL
COMBUSTION ENGINES

Walter Scott Burn, Hartlepool, England, assignor
to The National Gas and Oil Engine Company
Limited, and Alfred Bickerton Balmford, Ashton-
under-Lyne, England, and Walter Scott
Burn, Hartlepool, England

Application November 13, 1935, Serial No. 49,634
In Great Britain November 13, 1934

10 Claims. (Cl. 123—65)

This invention relates to the scavenging arrangements of two stroke oil engines and has for its primary object to provide an improved constructional form of pump and assemblage of valve and operating gear which will be particularly compact and efficient when compared with arrangements heretofore proposed.

Another object is to provide a simple and highly efficient scavenging air pump that is capable of being placed immediately adjacent to the cylinder of a two stroke cycle internal combustion engine without the usual delivery pipes or air receivers, and capable of being precisely timed and given the proper amount and rate of movement to deliver first scavenging air and then supercharging air at any predetermined time relative to the exhaust and scavenging periods of the main cylinder and at the requisite rate and pressure, thus entailing a minimum of work in compressing and delivering the air and, because of this cooperative action with the port openings, causing a reduction in the excess air ratio required for accomplishing the scavenging operation.

The pump of this invention comprises a vane-like displacer pivoted at one extremity for angular movement within a sector-shaped casing communicating through ports with an air source and with the scavenging and supercharging air inlet of the engine cylinder, means driven by the engine for oscillating said displacer to draw air into said sector-shaped casing from the air source and to expel such air into the engine cylinder and valve means, also driven by the engine, controlling the opening and closing of said ports.

The operating mechanism for imparting angular movement to the displacer may be an eccentric gear or a cam, roller and return spring, or return mechanism, but in any case it is preferred to arrange this operating mechanism to act on the displacer in the vicinity of the pivot or hinge of the latter in such manner as to keep the travel of the operating mechanism within relatively small dimensions. This arrangement and the angular form of the pump ensure that, while utilizing an operating gear of small dimensions possessing also only small movement, a large total displacement shall be obtainable, the pump being primarily intended for use with relatively large air displacements at low pressures.

For air sealing purposes, labyrinth grooves are formed around the outside of the displacer and only a small running clearance is allowed.

Pump suction and discharge are preferably

controlled by a single valve which may be a semi-rotary valve oscillating in a sector shaped casing and suitably operated by cam, roller spring and lever mechanism which enables it to serve first as suction valve to connect the pump to the scavenging air source while cutting off delivery to the engine cylinder and then as scavenge pump delivery valve to scavenge and supercharge the engine cylinder while cutting off the suction port. Cam operation of the displacer is preferred as this enables a precise control of air delivery to be obtained.

In the case of unidirectional engines the displacer operating cam profile can be made to give the requisite relatively quick delivery to coincide with the cylinder scavenging and supercharging periods as controlled by the piston and cylinder ports, while the return or suction stroke can be made more slowly over the remaining greater period, thereby reducing the suction or negative pressure.

To make the pump reversible, the cam operating the displacer and that operating the valve can be symmetrical and suitable "lost" motion arranged in the shaft driving coupling to give the correct relative timings for either direction of rotation.

It is preferred to have a separate pump associated with each cylinder, each with its required operating mechanism, operated from a shaft running parallel to the displacer and parallel to and driven from the main engine crankshaft. The driving shaft can be used for operating other service pumps such as the fuel pump etc. The pump casing is attached directly onto one side of the cylinder, the general arrangement being such as to cause a minimum of clearance volume and changes of direction of the incoming or out-going air between the scavenge pump air inlet main and the cylinder ports.

The construction of the control valve is such as to give a good flow of air into the scavenge pump from the air source (which may be an air suction belt embodied in the main cylinder casing) and also to facilitate the discharge of air into the scavenge belt of the main cylinder. The valve construction is, furthermore, such as to enable it to be withdrawn from its casing without dismantling the same by having detachable bearing pivots.

The shaft operating the scavenge pump valve may be that which drives the scavenge pump flap or it may be a separate shaft.

As an alternative construction the suction and discharge or control valve may be a flat

valve operated by suitable rockers controlling a port to the cylinder belt and one to the suction chamber. This arrangement gives reduced clearance volume.

5 If required, the pump can be made double acting, with two valves for supplying either two single acting cylinders or one double acting cylinder.

In order to obtain a high volumetric efficiency 10 from the aforesaid scavenge pump and to eliminate any negative suction pressure in the pump which may cause oil to be drawn into the pump from the region of the operating mechanism, the aforesaid pump or pumps may be charged by a 15 primary blower separately or independently driven.

The detail construction of the pump is such as to enable the flap to be removed without disturbing the casing. This is aided by fixing the 20 flap by studs to the pivot shaft.

The accompanying drawings illustrate one way of carrying the invention into effect.

In said drawings:

Fig. 1 is a sectional elevation viewed as if 25 taken on the line 1—1 of Fig. 2;

Fig. 2 is a view at right angles to Fig. 1, looking in the direction of the arrow x thereof and with one half in section upon the line 2—2 of Fig. 1;

30 Fig. 3 is a diagram of the cam associated with the scavenge air control valve, indicating how the valve positions illustrated in Figs. 4, 5, 6 and 7 are derived;

Figs. 4, 5, 6 and 7 represent different cycle 35 positions of the control valve; and

Figs. 8, 9 and 10 are diagrams showing how certain valve and piston positions are related.

Referring first to Figs. 1 and 2, the air pumping element or displacer comprises a flat flap 40 portion 3 adapted, in the position shown, to lie close to the engine frame 4 which carries the cylinder 5 of which a part only is illustrated. This cylinder is preferably, though not necessarily, adapted to be scavenged in the manner 45 described in my copending application Serial No. 49,632 filed November 13, 1935 for Internal combustion engines. The flap part 3 is curved at its lower end as indicated at 6 to carry an offset portion 7 which is removably connected by 50 studs 8 to the flattened surface of a rock shaft 9.

The shaft 9 is supported at each end in a roller bearing 10 mounted in the side walls 11 of a casing having a top wall 12 concentric with the shaft. The upper end of the flap portion 3 has a flange 13 curved to suit the casing wall 12 and there are also side flanges 14 to engage the casing side walls 11, the whole being stiffened by webs 15. The flap flange 13 is shown 60 to have a set of grooves or channels 16 to serve as a packing, said grooves being extended downwards along the side flanges 14 for the same purpose. Labyrinth packing 17 secures air tightness at the bearings 10 and a packing strip 18 65 adjustably attached to the casing by studs 19 engages the shaft 9 for a similar purpose.

The flap as a whole is adapted to be moved inwardly (toward the cylinder) to the extreme position shown against the returning action of 70 springs 20, the floating abutments 21 of which are coupled by links 22 to lugs 23 on the flap. These lugs and the links 22 are spaced sufficiently far apart to permit a cam 24 to engage a roller 25 carried upon a roller bearing 26 by a 75 shaft (not numbered) which is stationarily

mounted in bosses 27 formed in the flap. Said cam 24 is carried on a cam shaft 28 which is driven from the engine in any suitable way. At the upper end of the flap is a pocket 29 in communication with the flap casing, having a 5 spring loaded relief cover 30. Below said pocket level is a semi-rotary valve 31 adapted to cover and uncover a suction port 32 leading to an air belt 33 around the engine cylinder and also to cover and uncover a port 34 leading to the cylinder. 10

This valve 31 operates in a cavity 35 provided in the engine frame 4 and has arms 36 detachably fixed as by a nut 37 to a pivot 38 itself attached to a ball bearing 39 removably secured to the frame 4 and casing wall 11. One end of one of the pivots 38 is extended and formed as a crank 38x connected by a rod 40 to a lever 41 free to rock about a shaft 42. Compression springs 43 react between a stationary abutment 44 and an abutment 45 pivotally connected by a fork 46 to the lever 41, and a cam 47 on a shaft 20 48 acting through a roller 49 serves to rock the lever 41 against the spring action.

The cams 24 and 47 rotate at engine speed. 25

The timing of the scavenge air displacer 3 and control valve 31 will be understood from a consideration of the diagrams shown in Figs. 3 to 10.

As indicated in Fig. 8, when the time for exhaust lead is completed the engine crank is 20° from the bottom dead centre and the scavenge air displacer 3 commences movement towards its opposite extreme position shown in Fig. 10, where the whole of the air previously drawn into the casing is discharged. The cam 24 in doing this has moved angularly through 90° or thereabouts. Approximately 85% of the air is discharged when the cam 24 has moved angularly through 70° or thereabout, corresponding 40 to exhaust cut off which is the condition shown in Fig. 9. In passing from the position of Fig. 9 to position of Fig. 10, air is admitted for supercharging, the exhaust being already closed. 30

Referring now to Fig. 3 it is therein shown the position which the roller 49 for operating the semi-rotary valve 31 assumes in relation to the cam 47 at four angular intervals designated A, B, C and D, producing the valve conditions correspondingly designated A, B, C and D in Figs. 4, 5, 6 and 7.

While the cam 47 is in position such that its circular portion of smaller radius engages said rotary valve roller 49, the valve 31, as shown in Fig. 4, keeps the suction port closed and the inlet port 34 to the cylinder full open. 55 This condition exists while the piston is passing from position Fig. 9 to position Fig. 10. During upward travel of the piston from the position of Fig. 10 i. e. through the real compression period of the cycle—the valve 31 remains quiescent, covering the suction port, but later, in the vicinity of the firing point, the roller 49 is gradually moved, as shown in Fig. 3, from position A to positions B, C and D, the valve conditions produced being shown in Figs. 4, 5, 6 and 7. As will be understood, the valve 31 thus gradually uncovers the suction port 32 and covers the delivery port 34, the latter being, however, independently closed by the piston while the valve 31 is closing. During the exhaust portion of the 60 outward, or downward, stroke of the piston, the delivery port 34 is kept closed by that cylindrical portion of the cam 47 which is of larger radius, until the position of Fig. 8 is reached, whereupon the roller 49 passing through its cycle 70 75

positions D C B A in movement off the cam portion of larger radius onto the portion of smaller radius causes the valve 31 to gradually cover the suction port 32 and to uncover the delivery port 34, which are the conditions requisite for operation as represented by Figs. 8, 9 and 10.

What I claim is:—

1. A scavenge pump for two stroke internal combustion engines, comprising in combination with an engine, a vane-like displacer pivoted at one extremity for angular movement within a sector-shaped casing attached at the side of the engine cylinder, said casing having communication through ports with an air source and with the scavenging and supercharging air inlet of the engine cylinder, means including an outside separate shaft driven by the engine for oscillating said displacer to draw air into said sector-shaped casing from the air source and to expel such air into the engine cylinder, and valve means also outside and driven by the engine to control the opening and closing of said communication ports according to the timing with the cylinder's cycle of engine operation.

2. A scavenge pump according to claim 1, wherein the air displacer is oscillated by operating mechanism including a cam acting thereon in the vicinity of its oscillation pivot.

3. A scavenge pump according to claim 1, wherein a single valve is operated to control the alternate intake and expulsion of air to and from the sector-shaped casing.

4. A scavenge pump according to claim 1 wherein the valve means comprises a semi-rotary valve which is oscillated in a sector shaped recess forming an extension of the displacer casing and having in its arcuate face valve ports communicating with the air source and the engine cylinder, respectively, said ports being alternately opened and closed by the oscillation of said valve so that it alone controls both the intake and expulsion of air to the displacer casing.

5. A scavenge pump according to claim 1 characterized by the fact that the valve means includes an oscillating member mounted in a receiver space upon detachable bearing pivots which permit of its withdrawal from the casing without dismantling, and said member alone serves to control both the intake and expulsion of air to the displacer casing.

6. A scavenger pump according to claim 1,

characterized by the fact that the displacer is in the form of a flap and is detachably mounted upon a pivot shaft so as to be removable from the sector-shaped casing without disturbing the latter.

7. A scavenge pump according to claim 1, characterized by the fact that the displacer oscillated within the sector-shaped casing is provided with labyrinth grooves around its outer sides and top.

8. A scavenge pump according to claim 1, characterized by the fact that the mechanism for operating the displacer vane and the mechanism for actuating the valve means comprises means adjustable as to timing so as to permit the pump to be operated in either direction of rotation of the motor.

9. A scavenge pump for internal combustion engines, comprising a sector-shaped casing fastened to the side of the engine cylinder, a vane-like displacer mounted to oscillate in said casing, a passage for air to be drawn from a supply source into the displacer casing, a passage for air to be discharged from said casing into the cylinder, a valve controlling both of said passages so as to alternate the opening thereof according to the movement of the displacer within the casing, a shaft outside the cylinder driven by the engine crank shaft and carrying a cam for oscillating the displacer member, and means coordinated with said outside shaft for operating the said passage control valve.

10. A scavenge pump for internal combustion engines, comprising, in combination with an engine cylinder, a sector-shaped casing fixed on the outer side of the cylinder, a flap form of displacer mounted to oscillate in said casing, a passage for air to be drawn from a supply source into the displacer casing, a passage for air to be discharged from the casing into the cylinder, an oscillating valve controlling both of said passages so as to alternately open and close the same, a shaft supported on the casing outside the cylinder and carrying a cam for oscillating the displacer member, and another shaft mounted on the casing also outside the cylinder for actuating said passage control valve through linkage members; both of said outside shafts being driven by and in timing with the crank shaft of the engine.

WALTER SCOTT BURN.
